(57) **CLAIM**

The ornamental design for a lamp as shown and described.

DESCRIPTION

FIG. 1 is an isometric projection view of a lamp embodying my new design;

FIG. 2 is a front isometric view thereof;

FIG. 3 is a rear isometric view thereof;

FIG. 4 is a left side isometric view thereof;

FIG. 5 is a right side isometric view thereof;

FIG. 6 is a top isometric view thereof;

FIG. 7 is a bottom isometric view thereof; and,

FIG. 8 is an enlarged view of the area labeled “8” as shown in FIG. 1.

The broken lines depict environmental subject matter and form no part of the claimed design. The additional dotted-dashed broken lines encircling the enlargement areas in FIGS. 1 and 8 depict the boundaries of the enlargement and form no part of the claimed design.
